UNITED STATES PATENT OFFICE.

CHARLES A. HARTMANN, OF SAN ANTONIO, TEXAS, ASSIGNOR TO HARTMANN AUTO SAFETY LIGHT CORPORATION, A CORPORATION OF NEW JERSEY.

HEADLIGHT DEFLECTOR DEVICE.

Application filed June 29, 1923. Serial No. 648,507.

To all whom it may concern:

- Be it known that I, CHARLES A. HARTMANN, a citizen of the United States, residing at San Antonio, in the county of Bexar and 5 State of Texas, have invented certain new and useful Improvements in Headlight Deflector Devices, of which the following is a specification, reference being had therein to the accompanying drawings.
- 10 This invention relates to a headlight deflector device, and the object of the invention is the construction of a simple and efficient shutter device for a lamp or a headlight, preferably for a motor vehicle.
- 15 With this and other objects in view, my invention comprises certain novel combinations, constructions and arrangements of parts as will be hereinafter described, illustrated in the accompanying drawings, and 20 more particularly pointed out in the appended claim.

In the drawings:

- Figure 1 is a vertical, central, sectional view of a device constructed in accordance 25 with the present invention shown in a lamp or headlight.

- Figure 2 is a view, in front elevation, of a device constructed in accordance with the present invention, whereas

- 30 Figure 3 is a view in side elevation of the same.

Figure 4 is a perspective view of the primary plate of the shutter device, while.

- Figure 5 is a fragmentary view of the 35 same.

- Referring to the drawings by numerals, 1 designates the casing; 2 is the reflector, and 3 is the lamp or the headlight. The reflector 2 is provided with an annular groove 4 formed upon its outer face, in which groove 4 is placed a packing 5 that bears against the glass lens 6. The lens 6 also bears against the front of the shutter device 7, and against the annular cap 8.

- 40 The shutter device 7 comprises a ring-like body 9 which is provided with an annular flange 10 on its outer edge. The primary blade 11 and auxiliary blades 12 are supported upon the ring-like body 9 to reflect the rays from lamp 3 downwardly upon the roadway. The auxiliary blades 12 as 45 well as the primary blade 11 are beveled at their ends as at 13, Figs. 4 and 5, to fit the

contour of the inner face of the body 9. Each blade is provided at its ends with 55 tapering spurs 14 that extend through the body 9 and are bent at an angle to the body (Fig. 3) for holding the blades in position.

The primary blade 11 comprises the body 15 having a downwardly-extending center 60 bill 16 that affords a greater surface for the rays of the lamp 3 to strike against, so as to prevent the glare of headlights striking against the face, or blinding the vision, of the chauffeur in an approaching motor 65 vehicle.

By reason of the simple construction of the blades they can easily be assembled with the body 9 and fastened in position at a minimum cost; furthermore, if one of the 70 blades should become injured or deficient it can be easily removed and a new blade substituted therefor.

The ring-like body 9 is split, at 17, and its overlapping ends are fastened together 75 by suitable fastening means, for instance, by rivets 18.

While I have described the preferred embodiment of my invention, and have illustrated the same in the accompanying drawings, certain minor changes or alterations may appear to one skilled in the art to which this invention relates, during the extensive manufacture of the same and I therefore, reserve the right to make such alterations or changes as shall fairly fall within the scope of the appended claim.

What I claim is:

In a device of the class described, an open body, light deflecting strips extending transversely in said body for directing light downwardly and outwardly through the body, said strips being spaced vertically in said body with one strip positioned a greater distance from the strip below it than it is 90 from the strip above it, and a light concealing element extending downwardly from the intermediate portion of the last-mentioned strip across the relatively wide space and adapted to be positioned in front of a source 95 of light when said body is positioned in operative relation to a lamp body.

In testimony whereof I hereunto affix my signature.

CHARLES A. HARTMANN.
